SPUDDING MECHANISM FOR CABLE TOOL DRILLS

Herbert W. Thornburg, South Milwaukee, Wis.,
assignor to Bucyrus-Erie Company, South Milwaukee, Wis., a corporation of Delaware

Application February 10, 1938, Serial No. 189,809

4 Claims. (Cl. 255—11)

My invention relates to new and useful improvements in spudding mechanism for cable tool drills.

In such drills a rope passes, from a winch drum on the main frame, over a sheave at the upper end of a very slightly inclined boom, and thence vertically downward into the hole which is being drilled in the ground. At the lower end of this rope is a string of percussion drilling-tools.

During drilling, and especially when drilling shallow holes in rock, there is a tendency to throw slack into the rope at the end of each upstroke of the tools. Then too, on the downstroke, the rope is stretched and has a tendency to untwist. And, when the rope becomes slack at the end of the upstroke, the rope tends to twist up again. This upstroke and downstroke is called "spudding."

The net result of these tendencies is for the coils of rope on the drum to expand, and for some coils to become crossed over other coils. This damages the rope when pulled tight when uncoiling from this crisscrossed condition.

Various expedients have been devised in the past to partially clamp the rope, in an attempt thereby to keep the coils in their proper successive position on the drum. But in such a device the clamp must be loose enough to permit the free hoisting and lowering of the tools, and such a clamp is not only inefficient for its main purpose, but also causes considerable wear to both rope and clamp.

Accordingly it is the principal object of my invention to provide a slack-holding device which shall be efficient and shall not be open to the above objections. This I accomplish by an automatic device which clamps the rope against winding or unwinding on the drum during spudding, and completely unclamps the rope at all other times.

In addition to my principal object, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description, the same reference number is applied to the same member or to similar members.

Figure 1 is a side elevation of a drill embodying my invention.

Figure 2 is a plan view, partly in section, of the sheave and associated clamp of my invention, taken, at a slight inclination from the vertical, along the lines 2—2 of Figure 3.

Figure 3 is a side elevation, partly in section, of the same sheave and clamp, taken along the lines 3—3 of Figure 2.

Figure 4 is a plan view of a portion of Figure 1 taken along the lines 4—4 of Figure 1.

Referring now to Figure 1, we see that 11 is the main frame of a drill, supported by creeping traction 12, and during drilling by jacks 13.

The frame 11 supports a boom 14, a motor 15, a winch 16, a spudding gear 17, and associated driving connections, not numbered.

From the winch 16, a rope 18, runs over a heel sheave 19, thence under a spudding-sheave 20, thence over a sheave (not shown) at the top of the boom 14, thence down to the drilling tools (not shown).

The spudding gear 17 is clutched to and unclutched from a drive connection with the motor 15, by means of a clutch 21.

The spudding sheave 20 is mounted on one end of a spudding beam 23, pivoted coaxially with the heel sheave 19. The spudding beam is rocked up and down by the rotation of the spudding gear 17, acting through a pitman 24.

The winch 16 is controlled by means of a conventional clutch 37, brake, and hand-levers (not shown).

Comparing Figures 1 and 4, we see that lever 22, operating through an unnumbered series of linkages, controls yoke 38, which thrusts the male member of clutch 21 into or out of engagement with its female member. The male member is keyed to rotate with shaft 39 which in turn is rotated by wheel 40, belt 41, and motor 15. The female member of clutch 21, integral with pinion 42, floats free on shaft 39. Pinion 42 is in mesh with gear 17, which actuates pitman 24, as already described.

Turning now to Figures 2 and 3, let us consider the heart of my invention.

Heel sheave 19 is mounted for rotation and free lateral sliding on round shaft 25. There is also a polygonal or otherwise keyed shaft (shown here as square) 26, with its ends journaled in the frame 11. Two links 27 are mounted for lateral sliding on shafts 25 and 26. A lever 28 is mounted for rocking square shaft 26, and this lever is operated by rod 29, which extends to hand lever 22.

Mounted on links 27, for sliding radially with respect to heel sheave 19, is a yoke 30, carrying

a shoe 33, by means of its arm 35 being pivoted to the yoke at 31 and by means of a spring 32 and bolt 36, or in any other equivalent manner. Square shaft 26 has a cam 34, capable of engaging yoke 30, when the square shaft is appropriately rocked, and thus forcing shoe 33 to grip rope 18 against heel sheave 19.

By virtue of the control of square shaft 26 and clutch 21, both by the same hand lever 22, shoe 33 always grips rope 18, whenever spudding is going on; and at all other times frees the rope for raising or lowering the tools.

In this way, recoil of the rope 18 is, automatically and without the use of separate control mechanism, prevented during spudding, and yet the rope is left free to coil and uncoil at all other times.

Wherever, in the claims, I mention the support of the spudding sheave as being by "arms," the word "arms" is to be understood as also covering a single arm that serves the same purpose.

Having now described and illustrated one form of my invention, I wish it to be understood that my invention is not to be limited to the specific form or arrangement of parts hereinbefore described, except insofar as such limitations are specified in the appended claims.

I claim:

1. In the spudding mechanism of a cable tool drill, the combination of: a cable; a winch, on which one end of the cable is wound; a spudding sheave, over which the cable passes; arms, supporting this sheave; a horizontal pivot for the arms; spudding means for oscillating the arms, including control means therefor; a heel sheave, over which the cable passes; means, adjacent the pivot of the arms, for supporting the heel sheave for lateral sliding; means for clamping the cable to the heel sheave, during spudding; control means for the clamping means; and means, including an interlock, between the second control means and the spudding means, whereby the sec-

ond control means is automatically brought into play whenever the first control means is brought into play, and is automatically released whenever the first control means is released.

5. In the spudding mechanism of a cable tool drill, the combination of: a cable; a winch, on which one end of the cable is wound; a spudding sheave, over which the cable passes; arms, supporting this sheave; a horizontal pivot for the arms; spudding means for oscillating the arms, including control means therefor; a heel sheave, over which the cable passes; means, adjacent the pivot of the arms, for clamping the cable to the heel sheave, during spudding; control means for the clamping means; and means, including an interlock, between the second control means and the spudding means, whereby the second control means is automatically brought into play whenever the first control means is brought into play, and is automatically released whenever the first control means is released.

3. In the spudding mechanism of a cable tool drill, the combination of: a cable; a winch, on which one end of the cable is wound; spudding means, including a spudding sheave, over which the cable passes; means to reciprocate this sheave, to effect spudding, and control means for the reciprocating means; a second sheave, over which the cable passes, located intermediate the winch and the spudding sheave; and means, actuated by the spudding means, to clamp the cable to the second sheave, only during spudding.

4. In the spudding mechanism of a cable tool drill, the combination of: a cable; a winch, on which one end of the cable is wound; means for spudding the cable, including control means therefor; and means, intermediate the winch and the spudding means, and actuated by the spudding means for clamping the cable against recoil.

HERBERT W. THORNBURG.
